UNITED STATES PATENT OFFICE

WILLIAM C. BUCHANAN, OF FRANKLIN, MASSACHUSETTS, AND WILLIAM O. TOURJEE, OF PROVIDENCE, RHODE ISLAND, ASSIGNEES TO AMERICAN TYPE FOUNDERS COMPANY, OF JERSEY CITY, NEW JERSEY, A CORPORATION OF NEW JERSEY

PRINTING PRESS

Application filed June 10, 1926. Serial No. 115,075.

The present invention relates to printing presses and more particularly to such presses having an oscillating platen.

The principal features of the invention consists in the provision of a press of this type with:

1. Means for supporting the sheet feeding and delivery mechanism independent of the press frame.
2. Means for readily attaching or removing the sheet feeding and delivery mechanism.
3. Means for driving said mechanism from a single main shaft journaled independent of the press frame.
4. Means for automatically making pneumatic, electric and mechanical connections between the portable mechanism and the press source.
5. Means for automatically elevating the sheet feeding table and lowering the delivery table to maintain the tops of the feed and delivery piles at substantially constant elevations.
6. Means to throw the platen to impression-off position if a sheet is not fed to the press.
7. Means for readily detaching said throw-off mechanism.
8. Means for completing the movement of the throw-off before the completion of the platen movement.
9. Means for lifting sheets singly from the top of the pile of sheets and delivering them to the feed mechanism.
10. Means for adjusting the elevating mechanism for the pile of sheets to be fed and the lowering mechanism for the pile of printed sheets, to vary the extent of movement in accordance with the thickness of sheets.
11. An improved jogger mechanism.
12. An improved front stop and side register mechanism on the platen.
13. Improved means for permitting rapid raising or lowering of either the table supporting the pile of unfed sheets or the delivery table or both.
14. Improved suction pads for lifting sheets singly from the top of the feed pile.

Other features of novelty will be apparent from the description taken in connection with the drawings, in which:

Figure 1 is an elevation view of the right hand side of the machine, showing the portable feeder frame attached to the printing press, part only of the press proper being shown;

35 Referring more particularly to the drawings, in Fig. 1 a fragment of the press frame is designated by the reference character 10, the oscillating platen by 11, which is pivoted on the press frame at 12, and the fixed platen by 11^a. The press frame carries a main driving shaft 13 on which is keyed the large driving gear 14. An intermediate shaft 15 is journaled in a bracket 16 bolted to the press frame and carries an intermediate gear 17 meshing with the main driving gear 14.

40 45 The sheet feeding and delivery mechanism is mounted in a portable frame which is intended to be clamped to the press frame but which can be readily detached and moved away from the press frame. By this provision the sheet feeding and delivery mechanism is practically a self-contained unit.

50 Referring to Figs. 1, 2 and 3, the portable feeder frame comprises two side frames 18 and 19 of general L-shape design and of cut-55 away and channeled construction to give the required strength with a minimum weight of material. The two frames are bolted to cross members 20 and 21, as shown in Fig. 3, so as to form a rigid box-like frame. The entire 60 feeder frame is supported on four caster wheels 22, which are mounted in arms 23 pivoted at 24 in ears 25 carried by the side frames, and the feeder frame is adjustably supported on the arms 23 by adjusting screws 65 26 bearing on the arms 23 and provided with

nuts 27 by means of which the height of the feeder frame may be readily adjusted. The press frame is mounted on a base plate 28 which is provided with grooves 29 at each side, forming tracks in which the casters 22 70 are guided when the portable frame is brought up to the press frame.

The side frames 18 and 19 have journalled therein a main shaft 30 (Fig. 3) from which all of the cams and cranks for operating all 75 of the mechanism carried by the portable frame are driven. This shaft carries a large driven gear 31 (Figs. 1 and 2) of the same size and provided with the same number of teeth as the gear 14 on the printing press 80 shaft, and when this gear 31 meshes with the intermediate gear 17, the shaft 30 is driven in the same direction and with the same number of revolutions as the press shaft 13.

Sheet transfer mechanism

85

The sheets are fed to the platen from a pile supported on a table 32 and after receiving the impression are taken from the platen and deposited on a table 33 located between the table 32 and the press. The mechanism for transferring the sheets to the platen comprises two or more pairs of gripper fingers 34, 34^a supported at the outer end of an arm 35 (Fig. 1) which is keyed on a shaft 36 journalled in the side frames 18 and 19. Arm 35 is oscillated from a crank 37 on the main feeder driving shaft 30 by means of a connecting link 38. Since the crank shaft 30 makes one revolution for each printing cycle, the gripper fingers will make one complete oscillation from the sheet pile to the platen and back to the sheet pile per cycle. Any suitable structure and operating means may be used for cocking and uncocking the gripper fingers in timed relation to the operation of the platen, such as that disclosed in the copending application Serial No. 748,486, filed November 7, 1924, by Walter O. Hall and William C. Buchanan for printing 100 presses.

Sheet delivery mechanism

105

As in the case of the sheet feeding mechanism, the delivery mechanism consists of 110 two or more pairs of fingers which are adapted to be oscillated bodily to and from the platen. The delivery grippers are mounted in a pair of housings 39 which carry at each side a pair of rollers 41 tracking in cam guides 42 which are mounted on studs 43 secured on the inner faces of the side frames and are supported near their forward ends by rods 44 which are secured to the side frames at 45.

115 Referring more particularly to Figures 28 to 31, slidably mounted in each of the housings 39 is a block 351, and tying these blocks together is an angle bar 352. A hollow shaft 353 is journalled at its ends in the blocks 351, and in this shaft is a small shaft 354 which 120

125

130

projects through the blocks and carries on its projecting ends pinions 355 which mesh with racks 356 secured in the housings 39. Each pair of delivery fingers consists of an upper rotatable finger 357 and a lower relatively stationary finger 358. The upper fingers are formed with split collars 359 which are adapted to be clamped in adjusted positions on shaft 353 by bolts 360. The lower fingers are suitably supported for adjustment on the angle bar 352 as by means of clamping bolts 361 passing through upstanding tail portions of the fingers and through longitudinal slots in the angle bar 352. The blocks 351 are adapted to be held in adjusted positions in the housing by means of clamping bolts 362 secured to the blocks and projecting through other longitudinal slots 363 in the upper walls of the housing. When it is desired to adjust the position of the fingers relatively to the platen, as when sheets of different lengths are fed, it is only necessary to slack bolts 362, move the finger supports by hand to the correct position, and then tighten the bolts. In this adjusting movement, the meshing of pinions 355 with racks 356 causes rotation of the small shaft 354 and compels exactly equal movements of the blocks in both housings, thereby effecting a very accurate parallel movement of the finger supports mounted on said blocks. This provides a very easy and accurate adjustment of the delivery fingers through a wide range adapting the grippers for operation on sheets of widely different lengths without the necessity of varying the position of the head ends of the sheets on the platen.

A spring 364 surrounding shaft 353 has one end fixed to a collar 365 secured to said shaft 40 and has its other end fixed to a collar 366 in which the shaft is rotated and which is secured to angle bar 352 by screw 367. Spring 364 exerts a torque on shaft 353 in a clockwise direction, looking at Fig. 30, that is, in a direction to move fingers 357 into engagement with fingers 358. The upper fingers are moved in a contrary direction, or cocked, when they approach the limit of their movement away from the platen by means of an arm 368 adjustably secured on shaft 353 just inside the left hand housing 39, a roller 369 on the free end of said arm and a cam 370 (Fig. 1) supported on cam guide 42. Cam 370 consists of an inclined bar having its rear end pivoted on a lug upstanding from cam guide 42 and supported intermediate of its ends by another lug of greater height. When the grippers approach correct sheet depositing position, roller 369 runs under cam bar 55 and is thereby depressed, causing rotation of shaft 353 in a counter-clockwise direction, looking at Fig. 30, and cocking the fingers. The fingers are held open or cocked by a dog 373 on arm 374 engaging a shoulder 375 formed on a collar 376 secured to shaft 353.

Arm 374 is pivoted at its rear end on a pin 374^a projecting from block 351 just inside the right hand housing and at the opposite side of the machine from the cocking arm 368. As clearly shown in Fig. 30, arm 374 extends 70 from its pivot in the form of an arc over shaft 353 and terminates substantially below this shaft, carrying on its free end a roller 377. A spring 378 tends to hold arm 374 down. Roller 377 is so positioned that when the cocked fingers approach the limit of their movement toward the platen and the tail end of the sheet thereof has entered between the fingers, the roller comes into contact with the platen, or an abutment rigid therewith, and thus causes the arm 374 to move upward against the tension of spring 378, releasing shaft 353 and causing the grippers to close. 75

The operating mechanism for the delivery carriage, which moves the delivery grippers bodily towards and from the platen, as shown in Figs. 1 and 2, comprises a pair of levers 46 pivoted at their upper ends to links 47 which in turn at their forward ends are pivoted to the housings 39. The levers 46 have 80 a resultant motion produced by two trains of mechanism actuated from the main feeder shaft 30 and so designed as to produce quick movements of the grippers over or across the platen and a quick get-away from the platen, 85 with a substantial dwell following the movement from the platen. The levers 46 are accordingly fulcrumed to the upper end of arms 48 rigidly connected to a sleeve 49 supported by shaft 36. This sleeve 49 has rigid therewith a depending arm 50 (Figs. 2 and 3) which is pivoted to one end of a link 51, the other end of the link being formed with a fork 52 which works on a square block 52^a journalled on the shaft 30. This fork carries a 90 laterally projecting roller 53 which works in a cam track formed in the face of a disk 54 keyed on the shaft 30 outside of the side frame 19. The lower ends of the levers 46 are formed as gear segments, and meshing 95 therewith are similar segments 55^a formed on the upper ends of arms 55 which are secured to the end of a sleeve 56 rotatable on the shaft 36 located in the sleeve 49. The sleeve 56 which carries arms 55 is provided 100 with a depending arm 57 which is pivoted to a link 58, the forward end of which is provided with a yoke 59 working on a square block 59^b journalled on the shaft 30 and having a roller 59^a working in a cam slot formed 105 in the face of a disk 60 keyed on the shaft 30, between the side frame 19 and the cam disk 54. The levers 46 accordingly have a 110 resultant motion derived from the rotation of the gear segments on arms 55 and from their bodily oscillation over the segments by the rotation of arms 48. The cams are so formed as to produce quick movements of the grippers across the platen and a quick get-away from the platen, to avoid interference 115 120 125 130

with the platen and to abstract the printed sheet and move it away from the platen while the feeding grippers are conveying a sheet to the platen, and so as to produce a substantial dwell of the delivery grippers following the end of their movement away from the platen, to allow time for the platen to make its printing stroke before the grippers again move forward to take the printed sheet.

10 *Impression throw-off*

When the feeding grippers fail to feed a sheet to the platen, either because the sheet forwarding mechanism has failed to function properly, or because the supply of sheets has become exhausted, it is desirable to prevent offset on the packing or make ready. Mechanism is provided for performing this function which will now be described.

20 Referring particularly to Fig. 5, the main feeder shaft 30 has keyed thereon a cam 61 of the peripheral type which is adapted to operate a pitman 62 in one direction. This pitman is formed at its forward end as a yoke 63 working on a square block 63^b journaled on the shaft 30 and having a laterally projecting roller 63^a which is adapted to roll on the peripheral surface of cam 61. The rear end of this pitman has a pivoted connection at 64 with one end of a lever 65 pivoted on the feeder frame and a link 66 is also connected to the pitman at the pivot 64, which connects it with the outer end of a rod 67 slidably mounted in a lug 67^a on a bracket 67^b secured to the feeder frame. A compression spring 68 is coiled around the rod 67, and normally tends to push the pitman toward the left as viewed in Fig. 5. During normal operation, however, the pitman 62 is prevented from movement to the left by means of the latch 69 pivoted on the bracket 67^b and engaging a block 70 on the side of the pitman. The latch 69 is yieldingly forced in the direction to cause it to engage the block 70 by means such as the spring 69^a. Supported on the bracket beneath the tail end of the latch 69 is an electromagnet 71 the circuit of which is controlled by the sheet feeding grippers. The electromagnet 71 is connected by wire 72 to the feeder gripper 34^a and by wire 72^a to the plug 265 near the bottom of the frame (Fig. 1). The grippers 34 are connected by wire 73 to said plug so that when the grippers contact directly with each other, the circuit is closed and the electromagnet energized, current being furnished from a suitable source through socket 263 (Fig. 1) described hereafter. It will be understood that the gripper fingers 34 and 34^a are properly insulated so that the circuit will be closed only when the grippers contact with each other. Hence under normal operating conditions, when the feed grippers come into the sheet receiving position, a sheet will be inserted therebetween preventing electric

contact between them, but if no sheet is inserted, the gap which they normally form in the circuit of the magnet 71 will be closed and the magnet will be energized, attracting the latch 69 and releasing it from engagement with the block 70, thereby permitting the spring 68 to move the pitman to the left (Fig. 5). The upper end of the lever 65 is connected by means of a link 74 with one arm 75 of a bell crank pivoted on the feeder frame, the other arm 76 of which controls the platen throw-off devices. When the pitman 62 moves to the left, the toggle constituted by the lever 65 and the link 74 is straightened, throwing the arm 76 to the left from its normal position, as shown in Fig. 5, and causing movement of the platen to impression-off position by mechanism which will be described presently.

Rigid with the end of the platen throw-off 85 eccentric shaft 77 is a two arm lever 78 on one arm of which is journaled a roller 78^a and on the other arm is pivoted a latch 79. Normally the latch 79 engages the forward edge 80^a of a segmental lug 80 projecting laterally from the rocker R of the press and concentric with the eccentric shaft 77. When the lever 78 is locked in this position the eccentric shaft is in impression-on position. Pivoted on a pin secured to lever 78 is a second lever 81 on the tail end of which is journaled a roller 82. Lever 81 has a shoulder 81^a adapted to engage the rear edge 80^b of segmental lug 80 when lever 78 has been rotated in a clockwise direction to its platen throw-off position, thus positively locking the platen in this position. Latches 79 and 81 are biased by springs 83 and 84, respectively, to engage the segmental lug 80. Roller 82 on the tail end of latch 81 is adapted to engage an abutment 85 projecting inwardly from the arm 76.

The operation of the throw-off devices just described is as follows:

Fig. 5 shows the relative position of the parts when the platen is fully open and the eccentric shaft 77 is locked by latch 79 in impression-on position. When now the arm 76 is rocked to the left by the connections described, upon failure of the grippers to convey a sheet to the platen, the roller 86 on the tail end of latch 79 will engage the face 87 of arm 76 and consequently latch 79 will be rotated from engagement with the left hand end of lug 80. Roller 78^a will enter the recess 88 in arm 76, causing the lever 78 to be rotated clockwise when the platen moves toward closing position. During the initial part of this movement, roller 86 continues to engage the surface 87 and holds the latch 79 out of engagement with the lug until lever 78 has been rotated sufficiently so that the left hand end of latch 79 rides on the upper surface of lug 80. When lever 78 has been rotated to the limit of its clockwise move- 125

ment, the shoulder 81^a on latch 81 engages the right hand end of lug 80, thus locking lever 78 and the eccentric shaft rigid therewith in impression-off position. It is to be noted that the toggle 74, 65 is straight when arm 76 is in operative position with respect to the throw-off devices, whereby arm 76 is rigidly held against the cam action thereon of these devices. Upon movement of the pitman 62 to the right, in the continued operation of the press, lever 65 will be moved counter-clockwise, breaking the toggle 74, 65 and causing the arm 76 to move back to its normal position. Now when the platen 10 again approaches its open position, roller 82 on latch 81 will first come into engagement with an abutment 85 on arm 76, depressing the latch from engagement with the right hand end of lug 80, thereby releasing lever 78. In the continued movement of the platen, roller 78^a will engage the top of the lug 90 on the arm 76, and arm 76 will consequently be rotated to impression-on position before the completion of the platen 20 movement and will be locked in impression-on position by latch 79 snapping over the left hand end of lug 80. As the latch snaps into position, the roller 78^a rides free of the lug 90, and when the platen movement is completed, the roller 78^a engages the surface 89 on the arm 76.

The cam 61 for operating the pitman 62 is so formed and its operation is so timed with respect to the operation of the platen 30 and feed grippers that the roller 63^a on the pitman 62 will ride off the high part of cam 61 just before the cocking of the feed grippers as they approach the limit of their movement toward the platen. If at this 40 time the magnet 71 is energized, because of the failure of the grippers to feed a sheet, pitman 62 will be moved to the left, by action of spring 68, operating lever arm 65, which will straighten the toggle 74, 65 and thereby throwing the arm 76 to the left. As previously described, the movement of the arm 76 to the left will cause the platen to be moved to and locked in its impression-off position. The cocking of the grippers opens 45 the circuit of magnet 71 and hence latch 69 will engage block 70 when the roller 63^a on the pitman 62 rides onto the high part of cam 61, which it does when the grippers are 50 near their sheet receiving position. If now 55 the grippers receive between them a sheet, magnet 71 will remain de-energized and pitman 62 will remain locked by engagement of latch 69 with the block 70, but if a sheet is not received, magnet 71 will be energized 60 and cause the impression to be thrown off as described. The high part of cam 61 is designed to engage the roller on pitman 62 and move said pitman sufficiently to the right to slightly disengage block 70 so that the 65 operation of the latch by the magnet will not

be opposed by friction between the latch and the block.

Feed of sheets from the top of the pile

Sheets are automatically lifted from the pile on the feed table 32 and presented to the feed grippers by the mechanism which will now be described. Fastened on the shaft 30 inside the feeder frame is a cam 91 (Fig. 4) having a lateral cam groove in which operates a roller 92^a journalled on a pin projecting from the side of a yoke 92 which embraces and works on a square block journalled on shaft 30. The yoke is formed on the end of a pitman 93 which is pivotally connected to one arm of a bell crank 94 pivoted in the side frame 18. The other arm of the bell crank is connected to the lower end of a rod 95 which extends upwardly on the outside of the frame and is connected at its upper end to an arm 96 fast on shaft 97 journalled in the tops of the feeder side frames. The shaft 97 has secured thereto between the feeder side frames a pair of arms 98 the ends of which are loosely connected to studs 99 which are in a line parallel with the shaft 97 and are provided at their ends with blocks 100 which are adapted to slide in vertical guides 101 formed in the side frames. Swinging on the studs 99 are two depending arms 102 and tying the lower ends of these arms together is a bar 103. Two suction pad 105 are adjustably mounted on the bar 103 for lateral adjustment to adapt the lifters to sheets of different widths and the bar 103 is vertically adjustable on the arms 102 to provide for different sizes of suction pads. The suction pads are connected by short lengths 105 of flexible hose to a pipe 106 which extends laterally across the top 100 of the feeder frame and then downwardly outside of the side frame 18 (Fig. 1) and is connected to another flexible hose 107 which is in turn connected by connections to be later described, to another flexible hose 108 (Figs. 110 and 3) leading to the suction side of an air pump 109. The cylinder of this pump is pivoted at 110 to a lug projecting upward from the base plate 28 and the piston rod 111 is provided with a pin engaging a slot in an 115 oscillating arm 112 journalled on the press rocker shaft. The suction pads are actuated by mechanism which includes a cam disk 113 mounted on the shaft 30 between the side frames 18 and 19 and adjacent to the cam disk 91, said cam 113 having a groove in which is engaged a roller 114^a carried by a pitman 114, the end of the pitman being formed with a fork sliding on a square block journalled 120 on the shaft 30. The other end of the pitman 114 is pivotally connected with one arm of a lever 115 pivotally mounted in the feeder side frame 18, and the other end of this lever is connected to the lower end of a rod 116 125 130

which extends upwardly and is pivoted at its upper end to the end of an arm 117 rigid with a shaft 118 journaled at the top of the feeder side frames. A pair of arms 119 are rigid with the shaft 118 and have pins at their outer ends engaging slots 120 formed in the sides of arms 102. The cams 91 and 113 are so formed that the cam 91 will cause the suction pads to be moved up carrying a sheet and then to dwell throughout the rotation of cam 113 through an angle of about 270°. During this dwell in the vertical movement of the suction pads the swinging arms 119 cause the suction pads to move over towards the grippers and insert the sheet into the throats of the grippers and then to move back, after which the cam 91 causes the pads to move down for another sheet.

For separating the top sheet so that two or more sheets will not be lifted from the pile, there is provided a horizontal pipe 121 (Fig. 3) which extends across the rear of the sheet pile at the top thereof. This pipe is connected to flexible hose elements 122 which leads to nozzles 123 slidably mounted on the pipe 121. The pipe 121 passes down inside of the frame to a flexible hose 124 in turn connected, by connections to be later described, to a flexible hose 125 connected with the pressure side of the pump 109. The nozzles 123 are adjusted so as to be in line with the suction pads and they direct air blasts against the edges of the top sheets, separating these sheets and preventing adherence of the top sheet to the next one.

Pile elevating and lowering mechanism

The feed table 32 is adapted to be automatically raised, and the delivery table 33 lowered, by devices controlled by the level of the top sheet of the pile of sheets on the feed table 32. Secured to the front faces of the side frames 18 and 19, near the top thereof, is a pair of brackets 126 (Fig. 2) in the front ends of which is journaled a trip shaft 127. On shaft 127 inside the feeder side frames and adjacent to one of the suction pads is fixed a trip arm 128. This arm is formed with a split hub adapted to be clamped on the shaft so that the trip arm may be fixed in any desired lateral position in accordance with the width of the sheets being operated on. The adjacent suction pad has fixed thereto a laterally projecting pin 129 (Fig. 19) which is adapted to strike arm 128 and rotate shaft 127 to trip the mechanism for elevating table 32 and the mechanism for lowering table 33 when the level of the sheet pile sinks below a predetermined elevation. On shaft 127 outside the bracket 126 is fixed an arm 130 (Figs. 2 and 3) which carries a roller 130^a adapted to engage the upper arm of a pawl lever 131 fulcrumed on a depending part of the bracket 126. The lower end 65 of the lever 131 has a tooth engaging a notch

in a block 132 secured to the upper end of rod 133, a spring 134 tending to hold the tooth engaged with the notch. Rod 133 is slidably mounted in the lower end of the bracket 126 and in the projecting arm 135 of a lower bracket 154. A coiled spring 136 surrounds the rod 133 between the bracket 126 and a collar 137 secured to the rod, and operates to move the rod down when pawl lever 131 is released from engagement with the block 132. The lower end of the rod 133 has a pin and slot connection with a disk mask 138 which is rotatable on a stud 139 journaled at one end in the feeder side frame 19 and at the other end in a bracket 140 bolted to said frame. Fixed on stud 139 is a ratchet wheel 141 and a toothed gear 142, and an adjustable disk mask 142^a is located between the ratchet wheel and mask 138 and is rotatable on the stud. The ratchet wheel is adapted to be rotated by a pawl 143^b on an arm 143 pivoted on stud 139 and having rigid therewith on the opposite side of the stud from the pawl, an abutment 143^c adapted to engage a pin 144 projecting from the face of mask 138. The pawl arm 143 is pivoted to one arm of a rod 145, the other end of which is connected to a rocker arm 146 journaled in the feeder side frame 19. This rocker is also connected by a rod 147 to a pin on a crank disk 148 secured on the end of the shaft 30. Since the shaft 30 is continuously rotated during the operation of the press, once for each printing cycle, the pawl arm 143 will be continuously oscillated once for each printing cycle. When the mechanism is in non-tripped condition, however, oscillation of the pawl lever 143 will be ineffective, since the mask 138 covers all the ratchet teeth swept over by the pawl lever in its oscillation. Meshing with the gear 142 is a pinion 149 secured to the end of a shaft 150 (Fig. 2) journaled in the feeder side frames. Shaft 150 has fixed thereon a pair of bevel gears 151 which mesh with bevel gears 152 secured to the lower ends of screw shafts 153. These shafts are journaled at their upper ends in brackets 126 and at their lower ends in brackets 154. The table 32 is guided for vertical movement on the feeder side frames by means of yoke 155 secured to the rear corners of the table embracing and engaging vertical flanges 156 on the side frames, and the table is adapted to be operated by the shafts 153 being threaded in the yoke 155.

The automatic table moving devices operate in substantially the following manner:

When the level of the sheet pile on table 32 sinks below a predetermined level, the pin 129 on the suction pad holder will depress the arm 128, causing rotation of the trip shaft 127 and withdrawal of pawl 131 from the notch in block 132. The spring 136 will then instantly move the rod 133 down and rotate mask 138 in a clockwise direction. The rota-

tion of the mask in a clockwise direction uncovers a predetermined number of ratchet teeth by reason of its cut-away portion and hence on the return movement of the pawl arm, the pawl will engage the last tooth uncovered by said mask in its clockwise rotation, and rotate the ratchet through an angle determined by the number of teeth uncovered by said mask, thus rotating the screw shafts 153 and raising the table. In this return or driving movement of the pawl arm, the abutment 143^a will engage the pin 144 and return the mask and rod 133 to their cocked position, in which they are held against the tension of spring 136 by engagement of pawl 131 with the notch in block 132. A second or adjusting mask 142^a has a cut-away portion located relatively to the cut-away portion of mask 138, as indicated in Fig. 2. The position of the cut-away portion of this mask may be varied by simply rotating the mask by hand, a fingerhold pin 274 being provided for this purpose. The periphery of the mask 142^a is provided with teeth adapted to be engaged by a spring pawl 275, whereby the mask may be held in a number of adjusted positions. When the mask is moved counter-clockwise, it will shroud a number of ratchet teeth which would otherwise be uncovered by mask 138, and so cause the feed table to be elevated a lesser amount per actuation of the tripping devices, and conversely, when mask 142^a is rotated clockwise, it will unshroud a number of ratchet teeth, permitting the last one unshrouded to be engaged by the pawl when the mask 138 is tripped, thus causing rotation of the ratchet through a larger angle and hence a greater elevation of the table per actuation. Thus the automatic intermittent elevation of the table may be adjusted so that the degree of elevation per actuation may be varied to suit any thickness of the sheets.

The delivery table 33 is operated by a pair of vertical screw shafts 160 and 161 respectively. The right hand side of the delivery table is supported by a bracket 33^a secured to the side of the table, in which the shaft 160 is threaded. The upper end of the shaft 160 is journaled in a bearing 162 formed in a projection of a bracket 163 secured to the feeder side frame 18. The lower end of the shaft 160 carries a bevel gear 165 meshing with a bevel gear 166 keyed on a transverse shaft 167 journaled in the feeder frame. The left hand end of the shaft 167 carries a bevel gear 163^b meshing with a bevel gear 164 (Fig. 26). This gear has an integral sleeve 164^a threaded on the screw shaft 161, and the sleeve is journaled in a bracket 170 carried by the side frame 19, and is held in place by a collar 171 screw-threaded on the sleeve. The upper end of screw shaft 161 is rigidly secured to a bracket 33^b carried by the left hand end of the delivery table. Outside the screw

shaft 161 and in line with shaft 167 is a short shaft 167^a, journaled in the side frame 19, and having keyed thereto a bevel pinion 163^a meshing with bevel gear 164. Outside of the side frame 19, a spur pinion 172 is splined on the shaft 167^a, and meshes with an idler spur gear 172 journaled on a stud secured to the side frame. The idler gear 173 in turn meshes with the gear 142 which operates the feed table elevating mechanism.

Whenever the feed table is raised or lowered by the ratchet mechanism, as previously described, the delivery table is also lowered or raised in the opposite direction by the gear 142 which drives the pinion 172 by means of the idler gear 173. The shaft 167^a, being keyed to gear 172, rotates therewith and the bevel pinion 163^a causes the sleeve 164^a to rotate in the bracket 170, thereby raising or lowering the screw shaft 161 and moving bracket 33^b bodily in a vertical direction, causing corresponding movement of the delivery table. The gear 164 by meshing with gear 163^b drives the shaft 167, which transmits the drive to the other screw shaft 160. By having a non-rotative screw shaft to support the left hand end of the delivery table, the shaft does not have to extend above the table. This leaves an open space above the delivery table, so that the pile of printed sheets can be removed from the left hand or feeding side of the feeder, the left hand arm 46 being bent as shown in Fig. 2 so as not to obstruct the opening through which the sheets are removed.

Rear guides for the sheets on the delivery table are provided by a pair of vertical steel strips 276 secured at their lower ends to screw clamped sleeves 276^a transversely adjustable on a transverse rod 277 carried by arms 277^a bolted to the feeder side frames at the rear, as shown in Fig. 1. Similar rear guides for the sheets on the feed table are provided by a pair of steel strips 278 (Fig. 3) secured at their lower ends to screw clamped sleeves 278^a transversely adjustable on a transverse rod 279 bolted between the front portions of the feeder side frames. After the feed table has been elevated, the delivery pile can be removed from the front of the feeder by sliding the feed pile guides 278 to each side along the rod 279, or it can be removed laterally without elevating the feed table 32.

Both feed and delivery tables can be operated by hand, using a crank fitted on the squared end of shaft 139. If it is desired to raise or lower the feed table only, pinion 172 is disengaged from the idler gear 173 by sliding it on the extension of shaft 167. The crank will then drive the raising or lowering mechanism for the feed table, without affecting the delivery table, by the gear 142 meshing with the pinion 149. If it is desired to raise or lower the delivery table only, pinion 149 is disengaged from the gear 142 by sliding

it on an extension of the shaft 150. The crank will then drive the raising or lowering mechanism for the delivery table without affecting the feed table, by the gear 142 meshing with idler gear 173 driving the pinion 172.

Jogger mechanism

The jogger mechanism associated with the delivery table 33 is mounted in brackets 163 and 163^a supported above the table, and as shown in Figs. 8 to 12, comprises side jogger boards 175 and a head jogger pad 176 mounted and operated in accordance with the following description:

Adjustably fixed at their forward ends in the brackets 163 and 163^a are two parallel rods 177 which extend rearwardly at the sides of the delivery pile and have adjustably mounted on their rear ends a pair of brackets 178. These brackets are provided with rectangular slots to adjustably receive a square transverse rod 180. The brackets carry forwardly projecting arms 181 providing journals for an oscillating shaft 182. A crank 183 is mounted on one end of the oscillating shaft outside of the bracket journal, and the other end of the shaft is provided with a collar 184 which holds the shaft in position but permits its ready disassembly. The crank 183 is provided with a slot in which is engaged a pin 185 carried by a collar 186 adjustable on a reciprocating rod 187 slidably mounted in the bracket 163. The rear end of the rod 187 is connected with one arm of a bent lever 188 (Figs. 1 and 8) fulcrumed on the forward end of the bracket 163, the other arm of the bent lever being adapted to be contacted and operated by a projection 190 on the movable platen of the press. A spring 189 secured at one end to the bent lever and at its other end to the bracket 163 serves to return the bent lever subsequently to its operation by the press platen. A sleeve 191 is adjustably mounted on the square rod 180 and pivoted on this sleeve at 192 is a side jogger arm 194 which at its outer end pivotally supports the side jogger pad 175. A sleeve 195 is adjustably mounted on the oscillating shaft 182 and carries an upwardly extending pin 196 adapted to engage an oblique slot 197 in the side jogger arm 194. Mounted centrally of the squared rod 180 is a sleeve 198 adjustable on the rod, in which is slidably carried a head jogger rod 199 which at its other end pivotally supports the head jogger pad 176. A sleeve 202 is adjustably mounted on the oscillating shaft 182 and carries an upwardly extending pin 201 which engages a slot in the lower side of a sleeve 200 adjustably mounted on the head jogger rod 199.

Oscillation of the bent lever 188 under the influence of extension 190 and spring 189 reciprocates the rod 187, which causes the pin 185 carried by sleeve 186, by its engagement

with the slot in the crank 183, to oscillate the shaft 182. The pin 196 carried by the sleeve 195 mounted on the shaft 182, by its engagement with the oblique slot 197, will give the side jogger arm 194 a transverse reciprocatory motion. Also the head jogger pad 176 will be given a longitudinal reciprocatory motion by the pin 201 engaging the slot in the sleeve 200 carried by the rod 199. The mechanism for reciprocating the side pad 175 just described is duplicated at the other side of the delivery table, the parts being indicated by the reference characters 191^a, 192^a, 194^a, 195^a, 196^a, and 197^a. The left hand sleeve 191^a has a round bore engaging the square rod 180, so that the jogger pad on the open side of the feeder may be raised when the delivery pile is to be removed.

Sheet registering devices

The registration of the sheet on the platen is effected by the devices shown in Figs. 13, 14, 15 and 16. Fixed in the platen lugs, adjacent the gripper shaft 216 is a shaft or bar 203. The brackets 204 are slidably mounted on the shaft 203 and project forwardly over the face of the platen. These brackets are provided with a longitudinal bore receiving a stem 205 which carries at its outer end a sheet stop finger 206 which is provided with a rearwardly extending pin 207. A spring 209 is coiled around the stem 205, and fixed at one end in the bracket 204 and at its other end to the stem 205 so as to normally turn the sheet stop finger to an inclined position relative to the face of the platen. A stop 208 is secured on the end of the stem 205 and limits the upward movement of the finger 206. A sleeve 210 is adjustably mounted on the rod 203 and carries a pivot 211 on which is mounted a side register arm 212 on the outer end of which is slidably mounted a side register finger 213. The other end of the arm 212 carries a pin 214 which engages a helical slot in a cam 215 mounted on the gripper shaft. As the feeding grippers carry the sheet to the platen at the instant the feed grippers open, the sheet hits the two stop fingers 206 and is thus stopped with the edge of the sheet against the face of the fingers. As the feeding bar moves further it hits the pins 207 which lower the sheet down to the platen. As the press gripper shaft 216 rotates when the platen is opening and closing, the registering finger 213 is moved back and forth by the cam 215 engaging the pin 214 and causing the arm 212 to oscillate about its pivot 211.

Suction pads

Referring to Figs. 17 to 21, each of the suction pad housings 104 is provided with a bore 218 which receives a stem 217. The upper end of the bore 218 is expanded and has threaded therein a sleeve 219 through which the pad holder stem 217 extends. A

coiled compression spring 220 surrounds the stem 217 between the lower surface of the sleeve 219 and a collar 221 secured on the stem, and normally tends to hold the stem in its lowest position. The tension of the spring is adjustable by the sleeve 219. The upper end of the stem is threaded to receive a nut 222 by which the downward movement of the stem is limited, and a lock nut 223 is provided to hold the nut 222 in its adjusted position. The lower end of the stem is provided with a squared foot 224 engaging a slot in the pad holder 225 and held in place by screw 224^a by means of which the forward position of the pad holder may be adjusted. A rawhide hinge 226 connects the suction pad 227 with the holder 225. The pad holder is provided with an oblique recess 228 in which the pad holder 227 may be received when it is revolved upwardly about the hinge 226. The suction pad 227 is provided with a nipple 227^a on which the flexible suction tube 105 is fitted and the suction pad is provided with a milled slot 230 which forms the nozzle by which the sheet is lifted. The suction pad at opposite sides has pivoted thereto the lower ends 233 of a pair of rods 232 slidably carried by a plate 231 which is mounted on top of the housing 104 and clamped against the top of the housing by a nut 231^a, which also serves as a lock nut for sleeve 219. The upper end of each of these rods is threaded to receive a nut 234 which normally holds the suction pad 227 in its raised position, fitting into the recess 228, as shown in Fig. 17. Nuts 235 serve to lock the nuts 234 in their adjusted position. A coiled spring 236 surrounds each rod 232 and bears at its upper end against the plate 231 and at its lower end against a collar 237 adjustably mounted on each rod 232. The collar serves to adjust the tension of the spring 236. To limit the opening movement of the pad 227, a bar 238 is secured to the rods 232 just above the pad holder 225. The opening movement of the pad is limited by this bar striking the top of the pad holder. It may be clamped to the bars 232 in adjusted positions by means such as the set screws 238^a. In the downward movement of the suction pad about the hinge 226, in its extreme lower position, the lower surface of the suction pad is in the plane of the lower surface of the pad holder (Fig. 20).

In operation, when the housing is in the position shown in Fig. 17, which is the extreme position of its upward movement, the spring 220 holds the stem 217 in its extended position with the nut 222 bearing against the top of the sleeve 219, and the suction pad 227 is held in the position shown by the nuts 234 resting on plate 231. When the housing 103 moves downwardly and the pad holder 225 bears down on the top of a pile of sheets, the housing continues its downward movement and the pad holder is yieldingly pressed

against the top of the pile of sheets by the spring 220. At the same time, the plate 231 bearing against the springs 236 yieldingly forces the pair of rods 232 downwardly by bearing against the collar 237, thereby swinging the pad 227 into contact with the top sheet, its lower surface being in the plane of the lower surface of the pad holder 225, as shown in Fig. 20. The suction at the nozzle 230 causes the top sheet to adhere to the pad 227 and as the housing 103 is raised, the plate 231 engaging the nut 234 will tilt the suction pad 227 while the pad holder 225 is still bearing against the top sheet. This action positively raises the rear edge of the top sheet, thus permitting air from the nozzles 123 to be blown between the top sheet and the next sheet below, so that the sheets will not adhere. In this manner, the sheets of the pile are positively separated and lifted from the pile one by one. It will be understood that the movement of bar 103, previously described, causes the sheets to be moved to a position where they are taken by the gripper fingers and transferred to the platen.

Means for automatically connecting the feeder and press

The portable feeder frame and all of the mechanism carried thereby is adapted to be readily attached to or detached from the printing press frame by means which cause the automatic connection or disconnection of the mechanism carried by the feeder frame with the power sources in the press.

As shown in Figs. 1, 2, 22 and 23, the upper portion of the rear surface of each of the feeder side frames 18 and 19 is provided with a flat bearing surface 239 having a recess 240 (Figs. 2 and 23) which is adapted to receive a shaft 241 mounted in the press frame 10 and extending laterally from each side. The lower portion of the rear surface of each of the feeder side frames 18 and 19 has a flat bearing surface 242 which is adapted to abut the leg 243^a of an angle piece 243 bolted to the lower portion of the press frame 10 at each side by means of bolts 243^b. A screw 244 is threaded into each of the bearing surfaces 239 above the recesses 240. This screw is adapted to engage a socket in a clamp 245 pivoted on a similar screw 246 threaded into each of the bearing surfaces 239 below the recesses 240. Projecting from each of the surfaces 242 is a specially shaped screw 247, and just below these screws are the pivot bolts 249 on which are mounted the clamps 248 having sockets at their upper ends adapted to receive the screws 247, when swung to their upper positions. The lower clamp is provided with a laterally extending handle 250 which has pivoted thereon at 251 the lower end of a link 252. The upper end of the link 252 is connected to a laterally extending arm 253 of the upper clamp 245 so that when the handle 250 is operated, both

the upper and lower clamps will function at the same time. It will be understood that the clamping devices are the same on both sides of the feeder frame. A latch 254 is pivoted on each of the lower clamps at 255 and is provided with a tooth 256 adapted to engage a recess in the screw 249 when the mechanism is in the clamping position. A spring 257 attached at one end to the clamp and at the other to the latch, yieldingly holds the tooth 256 in its locking position. The latch 254 is for the purpose of holding the clamping devices in the position to secure the press and feeder together, that is to say, in the position shown in Fig. 22.

The securing devices above described are provided with means for automatically connecting the pneumatic elements on the feeder frame with the air pump on the press. As shown in Fig. 25, the leg 243^a of angle piece 243 is provided with a bore 258 connecting with nipple 259 on which is fitted the blower hose 125 leading from the pressure side of the air pump, and a registering bore 260 is provided in the feeder frame opening from the surface 242 and is connected with the blower hose 124 by means of a nipple 261. This blower hose in turn connects to the blower pipe 121 which supplies the pressure to the nozzles 123. A gasket 262 is fitted in a recess in the surface 242 and insures a tight joint between the mating bores when the feeder frame is clamped to the angle piece 243. A similar provision for the suction connections is made in the securing devices for the opposite side of the feeder and press as shown in Fig. 27. The bore 258^a connects with nipple 259^a on which is fitted the suction hose 108 leading from the suction side of the air pump, and the registering bore 260^a is connected with the suction hose 107 by means of a nipple 261^a. This suction hose in turn connects to the suction pipe 106 which supplies the suction for the suction pads. A gasket 262^a insures a tight joint between the registering bores.

Means are also provided for automatically making electric connections for the electrical units on the feeder frame with the electrical units in the printing press. A socket 263 (Fig. 1) is mounted on a bracket 264 bolted to the press frame and is electrically wired to the source of electrical energy in the printing press. This socket is adapted to be engaged by a plug 265 which is mounted on one of the cross members connecting the feeder side frames, and this plug is electrically wired to the electrical units carried by the portable feeder. It will be readily understood that when the portable feeder frame is brought up to the printing press and clamped against the press frame, the socket 263 will be engaged by the plug 265 making an electrical connection, and that when the feeder frame

is removed the electrical connection will automatically be broken.

When the feeder is either moved from or attached to the press it is necessary that the gears always mesh the same so as to have the same relative timing or sequence to each other. For this purpose a guide 266 (Figs. 1 and 4) is mounted on the feeder frame against part of the surface 239 and below the clamping device. This guide 266 is provided with an offset lug 266^a which when the feeder and press are brought together, slides through a slot 267 formed in one side of the rim of gear 14, if the gear is in proper position. If the gear is not in its correct position, the finger will strike its rim and hold the feeder and press from going together. Another guide 270 (Fig. 1) is mounted on the upper part of the bracket 16 which provides the journal for the intermediate shaft, and this guide likewise has an offset finger adapted to enter through the slot 271^a in gear 31 if the gear is in correct position. If the gear is out of position, then the finger will strike its rim in the same manner as just described above. When the frames are clamped together and it is desired to disconnect the portable feeder, the mechanism is slowly operated until the slots are opposite their respective guides. The frames are then disconnected, and when it is desired to again connect them, the mechanism of either which is out of timing will be operated until the slot in its gear is in alignment with the guide carried by the frame of the other. It will be seen, therefore, that these devices provide means whereby the feeder and press can be secured together only if the respective parts are in corresponding positions.

To sum up the method of securing the feeder to a press, it will be noted, as shown in Fig. 1, that the frame 10 of the press projects into the space between the side frames 18 and 19 of the feeder. In other words, the feeder frames 18 and 19 are spaced a distance slightly greater than the width of the frame 10 of the press so that when the feeder is rolled up to be connected to the press, it straddles a portion of the press frame. The press rocker shaft 241 projects laterally from each side of the press, and when the feeder is moved against the press, the projecting ends of this shaft seat in the recesses 240 on the feeder and are locked against displacement by the device shown in Figs. 22 and 23. Lower down, the press is provided with a pair of angle pieces 243 the front surfaces of which are adapted to contact with the corresponding flat surfaces on the feeder. The screws or pins 247 carried by the feeder project through apertures in the angle pieces and the surfaces just mentioned are held in contact by the locking means shown in Figs. 22 and 23 which engage the heads of the screws. Of course, as previously described, the feeder

cannot be connected to the press unless the parts of the feeder are in the same point in the cycle of operation as the parts of the press.

It will be seen, therefore, that the present invention comprehends a self-contained automatic feeder and delivery adapted to be detachably secured in operative relation with a platen press. When a job is of sufficient size to warrant the automatic feeding, the usual hand feed table is removed from the platen press and the automatic feeder described herein is rolled up and quickly attached to the press.

Having thus described the invention, what is claimed as new and desired to be secured by Letters Patent is:

1. Apparatus of the character described including in combination a platen press, a portable sheet handling mechanism supported independently of said press, said press having electric, pneumatic, and mechanical power sources, elements on said mechanism adapted to automatically connect with said sources when the mechanism is attached to the press, and means for detachably locking said mechanism to said press.

2. Apparatus of the character described including in combination a platen press, a portable sheet handling machine comprising a portable frame movable to a position entirely free of the press, sheet handling mechanism carried by said frame, devices for operating said machine, a shaft mounted in said frame for driving said devices, means for detachably securing said frame to the press and means for automatically establishing a driving connection between said shaft and an element of said press when said frame and press are secured together.

3. Apparatus of the character described including in combination, a printing press, a portable sheet handling mechanism, interfering elements on said press and mechanism, a base plate upon which said press is mounted, supporting rollers for said mechanism, guide tracks on said base plate for said rollers and means for detachably securing said mechanism to said press with said elements connected.

4. Apparatus of the character described including in combination a printing press, a portable sheet handling mechanism comprising a frame, means for supporting said frame independently of the press, means to guide said supporting means as the frame is moved against the press, a driving gear on said press, a driven gear on said frame and means to detachably lock said frame and press together with said gears properly meshed so that the press is in time with said mechanism.

5. Apparatus of the character described including in combination, a printing press, a portable frame movable to a position entirely free of the press and carrying sheet handling

mechanism, means supporting said frame independently of the press, a main shaft in said frame for operating said mechanism, a driving gear on said press, a driven gear on said frame for actuating said shaft, and means to detachably lock said frame and press together with said gears meshed in proper timed relation.

6. Apparatus of the character described including in combination a printing press, a portable frame movable to a position entirely free of the press and carrying sheet handling mechanism, means supporting said frame independently of the press, means detachably locking said frame and press together, a main shaft journaled in said frame for operating all of the parts of said mechanism, and means for driving said shaft from the press.

7. Apparatus of the character described including in combination a portable sheet feeding mechanism movable to a position entirely free of the press, a platen press having means to throw one of the platens to impression-on and -off positions, means to detachably secure the mechanism to the press, and means, associated with said mechanism and controlled by the failure to feed a sheet, to throw said platen to impression-off position.

8. Apparatus of the character described including in combination a printing press having an oscillating platen, a portable frame carrying sheet feeding mechanism, means to detachably secure said frame to the press, a shaft journaled in said frame and driven from said press, a pitman operated in one direction by said shaft and in the other direction by a spring, a latch preventing movement of said pitman under the influence of said spring, means to release said latch upon failure to feed a sheet, and means operated by the resulting movement of the pitman for tripping the platen to impression-off position.

9. Apparatus of the character described including in combination, a printing press having an oscillating platen and an eccentric shaft rotatable thereon and controlling the impression, means to feed sheets to the platen, an arm rigid with said eccentric shaft, a latch normally locking said eccentric shaft in impression-on position, a pivoted arm, a normally broken toggle connected to said pivoted arm, and means operative on failure to feed a sheet to straighten said toggle and move said pivoted arm, said pivoted arm when thus moved engaging and releasing said latch and having a surface adapted to cam the eccentric shaft arm during the initial closing movement of the platen to throw the impression off, and a lug on said pivoted arm to actuate said eccentric shaft to impression-on position during the opening movement of said platen, and before the completion of said opening movement.

10. Apparatus of the character described

including in combination, a printing press having an oscillating platen, a portable frame carrying sheet feeding mechanism, means to detachably secure said frame to said press, a shaft journaled in said frame and driven from said press, a cam on said shaft, a pitman operable in one direction by said cam, a spring operating said pitman in the other direction, a latch normally preventing operation of said pitman in said other direction, a magnet operable to release said latch upon failure to feed a sheet, a lever having one arm pivotally connected to said pitman, a second lever, a link connecting the other arm of said first mentioned lever with said second lever and forming with said other arm a normally broken toggle, and a trip arm rigid with said second lever adapted to trip the platen to impression-off position.

11. In a sheet delivery mechanism for printing presses having an oscillating platen, in combination, a frame secured to the front of the press, a lever pivoted to one side of said frame and having an arm projecting in the path of the platen so as to be rotated in one direction when the platen approaches open position, means for moving said lever in the other direction, a longitudinal rod pivoted to the other arm of said lever, and jogger mechanism operated by said rod.

12. Apparatus of the character described, including in combination, a printing press having an oscillating platen, a portable frame adapted to be detachably secured to said press, a sheet delivery table carried by said frame, jogger mechanism associated with said table, means to detachably secure said frame to said press, and means to actuate said mechanism from the oscillating platen.

13. Apparatus of the character described including in combination, a platen press having an oscillating platen, means to feed sheets one by one to said platen, a transverse rod secured adjacent the bottom edge of said platen, a bracket on said rod projecting slightly over the face of said platen, a stop finger pivoted on said bracket, yielding means normally holding said finger at an angle to the face of the platen, and a pin carried by said finger adapted to be engaged by said sheet feeding means to move the finger toward the platen.

14. Apparatus of the character described including in combination, a platen press having an oscillating platen, means to feed sheets one by one to said platen, a transverse rod secured adjacent the bottom edge of said platen, a bracket on said rod projecting slightly over the face of said platen, a stem mounted in said bracket, a stop finger on said stem, yielding means normally holding said finger at an angle to the face of the platen, and a pin carried by said finger adapted to be engaged by said sheet feeding means to move the finger toward the platen.

15. In a printing press having an oscillat-

ing platen and a gripper shaft rotatable in the platen lugs, a rod secured in the platen lugs adjacent said gripper shaft and parallel thereto, a side register arm pivoted on said rod, and a cam mounted on said gripper shaft 70 engaging said arm for moving it back and forth.

16. Apparatus of the character described including in combination, a press having an oscillating platen and a gripper shaft rotatable in the platen lugs, a rod secured in the platen lugs, a bracket on said rod extending over said platen, a stop finger pivoted on said bracket, yielding means normally holding said finger at an angle to the face of the platen, means to feed sheets one by one to said platen, a pin carried by said finger adapted to be engaged by said sheet feeding means to move the finger toward the platen, a side register arm pivoted on said rod, and a cam mounted on said gripper shaft 75 engaging said arm for moving it back and forth.

17. Apparatus of the character described including in combination, a platen press, a portable frame carrying pneumatic sheet feeding mechanism, a base plate upon which said press is mounted, an air pump mounted on said plate and actuated by the press, means detachably securing said frame to said press, and means automatically providing pneumatic communication between said mechanism and pump, when the frame is secured to the press.

18. Apparatus of the character described including in combination, a platen press having a shaft projecting from both sides thereof and located at the front of the press, a portable frame carrying sheet handling mechanism and means for detachably securing the frame and press together including parts on the frame cooperating with said shaft.

19. Apparatus according to claim 18 wherein the frame is provided with recesses adapted to receive the projecting ends of said shaft and also with devices to lock the shaft 110 in these recesses.

20. Apparatus of the character described including in combination, a platen press, a portable frame carrying sheet handling mechanism and means for detachably securing the frame and press together including pins on one of said parts adapted to project through apertures in the other, and means for locking said pins against withdrawal.

21. Apparatus of the character described including in combination, a platen press having a shaft at the forward side thereof, a portable frame carrying sheet handling mechanism and means for detachably securing the frame to the press including sockets in the frame adapted to receive said shaft and pins in one of said frame or press parts adapted to project through apertures in the other part, and means operable by a single 125 130

operation to lock the shaft in the recesses and the pins against withdrawal.

22. Apparatus of the character described including in combination a printing press, a portable frame carrying sheet handling mechanism, a gear on said press, a gear on said frame, means for detachably securing said press and frame together with said gears in mesh only when the gears are at the same 10 points in the cycle of operations of the press and mechanism.

23. Apparatus of the character described including in combination a printing press, a portable frame carrying sheet handling 15 mechanism, a gear on the press, a gear on the frame, means to detachably secure said frame to the press with said gears in mesh, and means to hold said parts from coming together except when the gears are at the same 20 points in the cycle of operation of the parts, including a projection on each part and a slot formed in the rim of each gear, the width of the slot being just sufficient to receive the projection so that if the gears are not in timed relation the projections will strike the rims and prevent the parts from going together.

24. Apparatus of the character described, including in combination, a platen press, a self-contained portable sheet handling mechanism including means to detachably secure said mechanism to said press in operative relation therewith, said sheet handling mechanism including a pneumatic device and the press including an air pump, and means for 30 automatically connecting said pump and pneumatic device when the mechanism and press are secured together.

25. Apparatus of the character described including in combination, a platen press, a self-contained portable sheet handling mechanism movable to a position entirely free of the press including means to feed sheets one by one to the platen, means to detachably secure said mechanism to said press in operative 40 relation therewith, and means to prevent securing of the mechanism and press together when the parts of the mechanism are out of time relative to the parts of the press.

In testimony whereof we hereunto affix our 50 signatures.

WILLIAM C. BUCHANAN.
